UNITED STATES PATENT OFFICE.

JULIUS ROST, OF MILWAUKEE, WISCONSIN.

HINGE FOR MOLDERS' FLASKS.

SPECIFICATION forming part of Letters Patent No. 508,983, dated November 21, 1893.

Application filed May 11, 1893. Serial No. 473,810. (No model.)

To all whom it may concern:

Be it known that I, JULIUS ROST, a citizen of the United States, residing at Milwaukee, in the county of Milwaukee and State of Wisconsin, have invented certain new and useful Improvements in Hinges for Molders' Flasks; and I do hereby declare that the following is a full, clear, and exact description of the invention, which will enable others skilled in the art to which it appertains to make and use the same, reference being had to the accompanying drawings, and to figures of reference marked thereon, which form part of this specification, in which—

15 Figure 1, is a perspective view of a corner of a molder's flask embodying my invention, and Fig. 2, is a perspective view on an enlarged scale of my improved hinge.

20 My invention relates to improvements in hinges for molders' flasks.

It has for its object to provide a hinge of this class which will be simple in construction, durable in use, comparatively inexpensive of production and which when applied 25 will prevent the splitting of the flask at those points at which it is secured.

With these objects in view the invention consists in certain features of construction and combination of parts, which will be hereinafter fully described and claimed.

In the drawings, 1 denotes the sides of a molder's flask and 2 the hinge. The hinge consists of two straps 2 and 3 united by a pivot bolt or pintle 4. Each strap has projecting from its edge ears 5 formed with screw holes 6. The ears of each strap are projected from each of its edges and are arranged at different distances from the pivot bolt. In po-

sition there are two hinges for each corner as shown in Fig. 1, one at the lower edge, and 40 one at the upper edge. The ears embrace the sides, and screws are inserted in the holes and screwed into the flask. By locating the ears at different distances from the pivot bolt, it will be noticed that when the screws are inserted they will not strike each other and that a firmer connection is secured.

7. denotes a screw hole in each of the straps through which screws 8 are inserted to form an additional fastening.

From the foregoing description taken in connection with the accompanying drawings, the operation and advantages of my invention will be apparent. It will be noticed that I secure a strong and durable hinge which may be secured in operative position without the least danger of splitting the flask thus overcoming a series of drawbacks heretofore existing.

Although I have shown my invention as applied to molders' flasks I would have it understood that I contemplate employing it for any other purpose to which it may be adapted.

Having thus described my invention, what I claim, and desire to secure by Letters Patent of the United States, is—

A hinge consisting of two straps pivoted together at their ends and provided with screw holes, each of said straps having an ear projecting from its opposite edges in the same direction and at different points from its ends and formed with screw holes, substantially as herein described.

JULIUS ROST.
